UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE-FRAME MECHANISM.

Application filed December 27, 1923. Serial No. 683,083.

To all whom it may concern:

Be it known that I, ELBRIDGE R. HOLMES, a citizen of the United States, residing at Worcester, in the county of Worcester and 5 State of Massachusetts, have invented a new and useful Tube-Frame Mechanism, of which the following is a specification.

This invention relates particularly to carpet looms of the Axminster type in which 10 the pile yarn is presented to the warp by successive tube frames each having a large number of yarn tubes mounted thereon in the usual manner.

It is the general object of my invention 15 to provide improved mechanism and devices for transporting the tube frames and for successively releasing the frames for presentation of the pile yarn to the warp.

Considerable difficulty has been heretofore 20 encountered in preventing accidental displacement or release of the tube frames during movement by the transporting chains and it is a particular object of my invention to provide improved devices for attaching 25 the tube frames to the chains, together with novel mechanism for releasing the frames when desired.

My invention further relates to arrangements and combinations of parts which will 30 be hereinafter described and more particularly pointed out in the appended claims.

A preferred form of the invention is shown in the drawings, in which—

Fig. 1 is a detail side elevation showing 35 a portion of my improved transporting chain and a portion of the operating mechanism for the locking devices thereon;

Fig. 2 is a front elevation of the parts 40 shown in Fig. 1 and shows also a tube frame in assembled relation therewith;

Fig. 3 is a bottom view of one of the attaching or locking devices on the transporting chains;

Fig. 4 is a sectional elevation of the parts 45 shown in Fig. 3;

Fig. 5 is a plan view of certain operating parts of the loom;

Fig. 6 is a side elevation of mechanism 50 for withdrawing the locking plungers; and

Fig. 7 is a front elevation thereof.

Referring to the drawings, I have shown a portion of a tube frame 10 (Fig. 2) having end brackets 11 secured thereto and 55 formed with a spool bearing portion 12 and an attaching portion 13. The portion 13 is

provided with a transverse opening near its upper end for a purpose to be described. The tube frame and its brackets may be assembled in any usual and convenient manner.

Each chain 14 is preferably formed with alternate single links 14^a and double links 16. The two parts of each double link 16 are spaced apart to provide an opening or slot adapted to receive the upper end of 60 the portion 13 of a tube frame bracket 11, as indicated in Fig. 2. The lower edges of the links 16 may be bevelled at 18 (Fig. 4) and the upper end of the portion 13 of the tube frame bracket may be correspondingly 65 bevelled to facilitate assembling of the parts.

A bearing support 20 (Figs. 3 and 4) is secured to one of each pair of double 70 link members 16 by screws 21 or in some other convenient manner, and provides an outer bearing for a plunger 22 which extends transversely through openings 23 in the double links 16. A head 24 limits inward movement of the plunger and a spring 75 25 engages the support 20 at its outer end and is connected to the plunger 22 at its inner end and thus yieldingly forces the plunger inward to the operative position 80 shown in Fig. 4.

If a tube frame is presented to the transporting chains, as indicated in Fig. 2, with the plungers 22 withdrawn, and the plungers are thereafter released, they will be 85 advanced through the openings 23 and also through the openings in the upper ends of the tube frame brackets, thus securely locking the tube frame to the chains. When thus secured in position the tube frame cannot become accidentally dislodged from the chains unless the plungers 22 are actually and intentionally withdrawn.

For securing and releasing the tube frames, I have provided the operating mechanism indicated in Figs. 5, 6 and 7. This mechanism comprises a special cam 30 on the loom cam shaft 31 which actuates a lever 32 connected by a link 33 to a bell crank 34. The crank 34 is mounted on a fixed pivot 35 and its upwardly extending portion 36 engages an arm 37 on a rod or shaft 38. The rod 38 is mounted in fixed bearings 39 in the loom frame and is yieldingly held in contact with the member 36 100 by a tension spring 40. A second arm 41 105

extends downward and forward from the rod 38 and is provided with spaced end portions 42, to which the heads 24 of the locking plungers are successively presented as 5 the chain links are advanced by the sprockets 15.

When a plunger head is thus presented, as indicated in Fig. 2, the cam 30 operates to swing the arm 37 in the direction of 10 the arrow *a* in Fig. 2, thus withdrawing the plunger and releasing the tube frame. The usual tube frame holders 50 are provided for receiving the tube frame and presenting it to the warp, thereafter returning 15 the tube frame to initial position. The holders 50 are pivotally mounted in bearings 51 formed at the front ends of levers 52 bolted to arms 53 mounted to swing about the axis of a heavy shaft 55. The 20 holders 50 are also provided with upwardly extending portions 56 having studs 57 to which are connected links 58 operable to rock the holders. This holder actuating mechanism is of a common type and forms 25 no part of this invention.

During the removal or presentation of the tube frames, the locking plungers are held inoperative by the arms 37 which, however, immediately move inward and release 30 the plungers as soon as a tube frame is returned to transporting position. The specific mechanism for withdrawing and releasing the locking plungers is intended to be illustrative only and other suitable mechanism 35 may be substituted therefor.

I have thus provided locking devices by which tube frames may be securely attached to transporting chains, and by which they may be positively released and thereafter 40 again attached during the operation of the loom.

Having thus described my invention and the advantages thereof, I do not wish to be limited to the details herein disclosed otherwise than as set forth in the claims, but 45 what I claim is:—

1. In a loom, a yarn tube frame, end brackets therefor having transverse openings in their upper ends, transporting chains 50 for said tube frame, locking devices slidably

mounted on said chains and extending through said transverse openings to detachably secure said tube frame to said chains, and means to withdraw said locking devices to release said tube frame. 55

2. In a loom, a yarn tube frame, end brackets therefor having transverse openings in their upper ends, transporting chains for said tube frame, each containing a succession of spaced double links, locking devices secured on said double links and extending through the transverse openings of said brackets when the latter are inserted in said links, thereby detachably securing said tube frame to said chains, and means 60 to withdraw said devices to release said tube frame.

3. In a loom, a yarn tube frame, end brackets therefor having transverse openings in their upper ends, transporting chains 70 for said tube frame, each containing a plurality of spaced double links, locking devices secured on said double links and extending through the transverse openings of said brackets when the latter are inserted 75 in said links, said devices being yieldingly movable to locking position, and means to withdraw said devices to release said tube frame.

4. In a loom, a yarn tube frame, end 80 brackets therefor, transporting chains for said tube frame, locking plungers mounted on certain links of said chains, said plungers being yieldingly movable transversely to engage said brackets and hold said tube frame 85 for movement with said chains, and mechanical means to withdraw said plungers to release said frame.

5. In a loom, a yarn tube frame, end brackets therefor, transporting chains for said tube frame having double links with bevelled sides spaced apart and having aligned transverse openings therein, and locking devices adapted to extend through said openings and to engage said end brackets to secure said tube frame to said chains. 90

In testimony where I have hereunto affixed my signature.

ELBRIDGE R. HOLMES.
